UNITED STATES PATENT OFFICE

2,279,234

METALLIC BOAT

Edward Heckmann, Columbia, Mo.

Application June 14, 1939, Serial No. 279,212

1 Claim. (Cl. 9—6)

This invention relates to metallic boats, and its general object is to provide a boat or vessel that includes a hull constructed entirely of sheet metal sections preferably disposed transversely of the hull and shaped and secured together to provide the ends, sides and bottom thereof.

A further object is to provide a boat including a hull made up of sheet metal sections that are flanged to facilitate securing the sections together, as the flanges are disposed in face to face abutting relation and fixed accordingly by welding or other suitable means in a manner to provide closed joints, thus eliminating open seams and cracks and thereby deterioration by rust, as the closed joints can be painted in their entirety and the fixed together flanges likewise act as reinforcing ribs which add materially to the strength and rigidity of the boat.

Another object is to provide boat hull forming sheet metal sections of various sizes and shapes, for the construction of large or small boats of different types, including row, sail and motor powered boats, having sides, sterns and bows of any desired or well known shape.

A further object is to provide boat hull forming sections each being made from a single flat metal blank stamped, cut or otherwise formed in the proper shape and marked to indicate the manner of bending the same into a section, and the blanks may be numbered for identification purposes to facilitate assembling the sections in hull formation.

Another object is to provide a boat that may include airtight compartments at the bow and stern thereof to eliminate all possibility of sinking.

A still further object is to provide a metal boat that is light in weight, simple in construction, can be easily, expeditiously and inexpensively constructed especially due to the use of the hull forming sections, yet the boat is extremely efficient in use and service.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a top plan view of a row boat constructed in accordance with the present invention.

Figure 2 is a sectional view taken approximately on line 2—2 of Figure 1, looking in the direction of the arrows.

Figure 3 is a sectional view taken approximately on line 3—3 of Figure 1, looking in the direction of the arrows.

Figure 4 is a perspective view of one of the intermediate sections used in the construction of my boat.

Figure 5 is a plan view of a blank from which the intermediate section of Figure 4 is formed.

Figure 6 is a fragmentary sectional view taken through a modified form of intermediate section, with a gunwale or carlock strip secured to the upper end of the side wall portion thereof.

Figure 7 is a fragmentary plan view of the blank from which the section of Figure 6 is formed.

Figure 8 is a fragmentary top plan view illustrating a modified form of hull construction.

Figure 9 is a fragmentary longitudinal sectional view taken through a further modified form.

Referring to the drawings in detail, and particularly to the form as shown in Figures 1 to 5 inclusive it will be noted that the hull of that form includes a plurality of intermediate sections 1, each being of identical shape and best shown in Figure 4, as well as formed from a blank 2, shown in Figure 5. The blank of Figure 5 is cut, stamped or otherwise formed from sheet metal into elongated rectangular formation, with triangular shaped notches 3 extending into the longitudinal edge portions thereof adjacent to their ends, the notches of each end being disposed in registration with each other, and extending between the apex or inner ends of the notches 3 are transverse fold lines 4, while longitudinal fold lines 5 extend along the length of the blank from end to end and intersect the point of juncture of the transverse fold lines with the inner ends of the notches.

The blank 2 is folded along the lines 4 and 5 to provide a bottom wall 6 for the section, upright walls 7, longitudinal flanges 8 disposed along the outer edges of the bottom wall and at right angles thereto, and side flanges 9 formed on the edges of the upright walls. The notches 3 are of an angle so that the walls 7 will be arranged at right angles with respect to the bottom wall, when the edges of the notches are disposed in abutting relation, as clearly shown in Figure 4. The abutting edges of the notches may be welded together.

Any number of sections 1 may be used, it de-

pending upon the length of the boat to be constructed, and they are disposed in side by side relation with the flanges 8 and 9 of the adjacent sections arranged in abutting engagement, as well as secured together, preferably by welding and for that purpose the outer edges of the flanges are beveled to provide seats or grooves for the welding material 10, which completely closes the joint between the flanges, thereby eliminating open seams and cracks, as well as the possibility of the formation of rust between the flanges.

It will be obvious from the foregoing that the flanges not only provide ample means to facilitate the joining together of the sections, but by arranging them in face to face abutting relation, they provide reinforcing ribs extending at equi-distantly spaced relation transversely of the hull throughout the major portion of the length thereof, thereby materially adding to the strength and rigidity of the boat, as will be apparent upon inspection of Figure 1.

The hull in the form of Figures 1 to 3, likewise includes in its construction, two metallic end sections at both the bow and stern thereof and the end sections are also bent or folded from blanks of sheet metal, but they differ from the intermediate sections, as will be noted upon inspection of Figure 3. The inner and outer end sections 11 and 12 respectively at the stern of the hull are provided with bottom walls and upright side and end walls 13 and 14 respectively, the side walls being of equal length and of the same length as the flanges 8 and the bottom walls being disposed at an upward inclination toward the stern. The innermost side wall of the inner end section 11 is welded to the outer flange of the outer intermediate section, as shown in Figure 3, and the other side wall is welded to the adjacent side wall of the outer end section 12, the latter side walls being of equal height and when secured together are flush with the inner side wall of the inner end section 11 to receive a deck plate 15 that is welded to the upper ends of the latter mentioned side walls 13 as well as to the outer side wall of the section 12 for cooperation with the side and end walls of the section 12 for cooperation with the side and end walls to provide airtight compartments 16, as will be apparent. The inner and outer end sections 17 and 18 respectively at the bow of the hull are similar in many respects to the sections 11 and 12, in that the sections 17 and 18 include angular bottom walls and upright side and end walls 19 and 20, with the bottom walls thereof disclosed at an upward inclination toward the bow, the side wall of the section 17 being welded to the flange 8 of the adjacent intermediate section 1, while the other side wall of the section 17 is welded to the inner side wall of the section 18, and the latter side walls have welded to the upper ends thereof a deck plate 21 which like the deck plate 15 is likewise welded to the end walls to provide an airtight compartment 22. The end walls 20 are inclined for disposal in substantially diverging relation with respect to each other toward the end of the bow which terminates into a flat outer end, due to the outermost side wall 19 of the outer end section 18.

From the above description and disclosure in the drawing, it will be obvious that when the sections 1, 11, 12, 17 and 18 are welded together that the bottom walls thereof provide the bottom of the hull and the end walls 7, 14 and 20 provide the sides thereof, and welded to the upper ends of the sides are gunwale strips 23

having oarlocks 24 mounted therein. However, it will be noted from Figure 3 that ample provision is made for receiving an outboard motor due to the extension of the outermost wall 13 above the deck plate 15. It will be further obvious that all of the parts are preferably welded together, and all of the joints are preferably beveled to provide grooves or seats for receiving the welding material 10, as clearly shown in Figures 3 and 9, thus reducing rust to a minimum and which tends to expedite the painting of the boat, due to the fact that open seams and cracks have been eliminated.

In the modified form of intermediate section 15 as shown in Figure 6, it will be noted that the upright wall 25 is disposed at an outward inclination with respect to the bottom wall 26, as distinguished from the right angle arrangement of the upright wall 1 with respect to the bottom wall 6, and such is accomplished merely by changing the angle of the triangular shaped notches, that is the notches 27 of the blank 28 are of less degrees than that of the notches 3. Otherwise the intermediate section of Figure 6 is identical with that of Figure 4.

While the sections may be of any size for constructing boats of various sizes, in the construction of large boats the sections are not only disposed in side by side relation and welded accordingly, but are likewise disposed in end to end relation, with the end walls welded together, and in that event the end walls that extend along the longitudinal center of the hull in fact provide a fore and aft bulkhead. Such a construction is shown in the modified form of Figure 8 which likewise discloses a pointed bow portion made up of a plurality of end sections 29.

In the modified form of Figure 9, the bottom wall of the bow is rounded, as distinguished from 40 the straight line construction of the form of Figures 1 to 3, otherwise the structure of Figure 9 is preferably similar to that of Figures 1 to 3.

While I have illustrated boats or vessels having three types of bows, it will of course be understood that a boat constructed in accordance 45 with my invention can be made with any shape of bow and stern, as the blanks from which the end sections are formed may be of different shapes for that purpose.

Any suitable floor may be provided for the boats, but I preferably provide a wood grating to rest upon the flanges 8.

It is thought from the foregoing description that the advantages and novel features of the 55 invention will be readily apparent.

It is to be understood that changes may be made in the construction and in the combination and arrangement of the several parts, provided that such changes fall within the scope of the appended claim.

What I claim is:

In a metal boat comprising a hull including a plurality of sheet metal elongated rectangular intermediate sections, each provided with a bottom wall and upright end walls, upturned relatively narrow side flanges formed on and extending along the length of the bottom wall, inwardly directed flanges formed on the ends of the upright walls and having their lower ends meeting the ends of the upturned flanges for engagement therewith throughout the width of the flanges, said sections being arranged in side by side engagement with the abutting flanges welded together; sheet metal elongated end sections at both the bow and stern of the boat, each end

section provided with a bottom wall and upright side and end walls, the innermost side walls of the innermost end sections abutting and welded to the flanges of the outermost intermediate sections and the intermediate side walls of companion end sections abutting and welded to each other for the end walls of all the sections to provide the sides of the boat and the outermost side walls of the end sections the ends of the boat, the bottom walls of the end sections being dis- 10

posed at an upward inclination toward their respective ends of the boat, metallic deck plates mounted on and welded to certain walls of the end sections to provide airtight compartments, metallic gunwale strips welded to the sides of the boat and extending inwardly therefrom, and the flanges and walls having beveled edges providing seats for receiving the welding material.

EDWARD HECKMANN.
